UNITED STATES PATENT OFFICE.

GEORGE W. BANKER, OF NEW YORK, N. Y.

IMPROVEMENT IN BARRELS.

Specification forming part of Letters Patent No. 159,064, dated January 26, 1875; application filed November 4, 1874.

To all whom it may concern:

Be it known that I, GEORGE W. BANKER, of the city of New York, State and county of New York, have invented an Improvement in Barrels, of which the following is a specification, reference being had to the accompanying drawing forming part of the same.

My invention relates to that class of barrels and kegs designed to contain volatile liquids, and for that purpose are intended to be coated on the inside with pitch or some suitable cement. My invention consists in the peculiar construction and combination, hereinafter particularly described, of two barrels, one within the other.

The accompanying drawing is a central longitudinal section of a double barrel containing my invention.

A is the inner barrel, which may be made either of staves or of a single sheet of wood sliced from a round log, and having only a single seam, as described in Letters Patent issued to me June 13, 1871, No. 115,807. B is the outer barrel, which may be similarly made. In putting these barrels together one within the other, there may be a free space, *i*, between them and no contact except at the hoops of the inner barrel, which I recommend to be carefully made and applied of even and uniform thickness throughout, and the diameter of the outer barrel such that its inner surface fits snugly upon the hoops of the inner barrel, so that the outer barrel, while made tight in all its seams, incases tightly the inner one, permitting no movement of the latter in the former. The heads of the two barrels are made and combined in the peculiar manner shown in the drawings. The head of the inner barrel is preferably, for cheapness, composed of two thicknesses of wood or plates, *a* and *b*, as shown in the drawings, which should be secured together by rivets or cement. The diameter of the outer plate *b* coincides with the external diameter of the end of the barrel A, the said plate resting on the ends of the staves, the latter being planed off, as shown, to receive it. The diameter of plate *a* coincides with the internal diameter of the barrel A, and sets down within the end of the staves, its edge being beveled, as

shown, to coincide with the taper of the barrel, forming thus, in fact, a dovetailed joint, and locking the head in the barrel, serving the purpose of a croze. The end hoop *c* of the barrel A is made to fit over the end of the staves and the edge of the plate *b*, the outer edge of the hoop coinciding with the outer surface of said plate. Then the head *g* of the barrel B fits down and rests upon the hoop *c* and plate A' within the chime of said barrel B, and is beveled on its edge to fit the inclination of the chime. The outer hoop *d* is then driven on, when it is evident the several plates composing the combined head will be locked securely in place. For greater strength a stay-hoop, *e*, may be applied and secured outside of the outer head. In place of two plates *a* *b* a single one may be employed with an annular beveled notch cut around its edge to receive the ends of the staves of the barrel A.

It is evident that the free space between these two barrels serves to secure the inner barrel against the effect of blows or other violence upon the outer one, there being no contact between them except at the hoops, where the resistance of the hoops obviates damage.

The advantages of the peculiar construction and combination of the parts constituting the heads are their simplicity, strength, and convenience of fabrication.

What I claim, and desire to secure by Letters Patent, is—

The combination of the plate *a*, locked within the end of the barrel A, the plate *b* resting on the said end, and beveled on the edge to fit the hoop *c*, the plate *g* resting on the plate *b* and hoop *c*, and beveled on its edge to fit the taper of the chime of the barrel B, the hoop *d*, and stay-hoop *e*, all constructed, adapted, and connected as and for the purpose specified.

Witness my hand this 2d day of November, 1874.

GEO. W. BANKER.
